(57) **CLAIM**

The ornamental design for a field wireless access point, as shown and described.

DESCRIPTION

FIG. 1 is a front, top and right side perspective view of a field wireless access point according to our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

FIG. 8 is a front, top and right side perspective view showing an environment wherein an extension antenna is connected. The broken lines in the drawing figures show portions of the field wireless access point that are not being claimed, and thus from no part of the claimed design.
